UNITED STATES PATENT OFFICE.

HERBERT HASTINGS, OF ROCHESTER, NEW YORK, ASSIGNOR TO ART IN BUTTONS,
INCORPORATED, A CORPORATION OF NEW YORK.

FEEDING-TABLE FOR BUTTON-BLANKS.

1,282,077.

Specification of Letters Patent. Patented Oct. 22, 1918.

Application filed November 16, 1915. Serial No. 61,889.

To all whom it may concern:

Be it known that I, HERBERT HASTINGS, of Rochester, in the county of Monroe and State of New York, have invented certain 5 new and useful Improvements in Feeding-Tables for Button-Blanks; and I do hereby declare the following to be a full, clear, and exact description of the same, reference being had to the accompanying drawings, 10 forming a part of this specification, and to the reference-numerals marked thereon.

My present invention relates to a feeding table for button blanks and has for its object to provide means for holding a plurality 15 of spaced button blanks in proper position for delivery to a series of work piece holders through the medium of any suitable transferring mechanism.

A further object of the invention is to 20 provide adjustable means for holding different size blanks in position upon a feed table for delivery to a series of work piece holders of any approved type. To these and other ends the invention consists in certain improvements and combinations of parts, all as 25 will be hereinafter more fully described, the novel features being pointed out in the claims at the end of the specification.

In the drawings:

30 Figure 1 is a plan view illustrating one embodiment of my invention;

Fig. 2 is a similar view with certain parts removed to more clearly illustrate the mechanism for properly centering the work 35 pieces upon the table;

Fig. 3 is an enlarged sectional view taken on line *a—a* of Fig. 1, and

Fig. 4 is a sectional view taken on line *b—b* of Fig. 1.

40 Similar reference characters in the several figures indicate the same parts.

Illustrating the present embodiment of the invention I preferably provide a feeding table for button blanks as indicated at 10, 45 upon which the work pieces or button blanks, previously prepared and assorted, are positioned by an attendant.

The feeding table is provided with equidistantly spaced notches 11 over which the 50 centers of the blanks, such as 12, are placed and held by pressure of spring fingers 13. However, as it is desirable to properly position the blanks so that they may be accurately located with their centers above the 55 slots in the plate, as well as with reference

to the periphery of the latter, the table is provided with centering devices or spacers which may be adjusted in accordance with the size and character of the button blank stock to be operated upon. The central portion of the table is provided with an annular hub or shoulder 14 surrounded by a ring 15 having outwardly projecting gage fingers 16, located between the slots 11 in the table. Also journaled on the hub, above the plate 60 15, is a ring 17 provided with a plurality of notches 18 which receive the short arms 19 of small bell crank levers pivoted on pins 20 on the plate 21 at the base of each gage finger 16. The arms 22 of each of the bell 65 crank levers extend laterally from their respective gage fingers across the slots 11 in the feeding table and are movable inwardly and outwardly, by an oscillatory movement of the ring 17, to vary the distance between 70 them and between the edge of the table whereby different size blanks may be accommodated and positioned at relatively 75 different points radially and circumferentially of the table. Overlying the hub of 80 the table and the ring 17 is the stationary cover plate 21 and arranged thereon are two pivotally mounted adjusting arms, or levers 25 and 32 by means of which the plate 15 and the ring 17 may be oscillated, the former 85 to position the gage fingers 16 laterally relatively to the slots in the table and the latter to move the fingers 22 inwardly or outwardly on the face of the table. The lever for adjusting the plate 15 is indicated by 90 25 and is pivoted at the point 26 on one of the pivot pins 20, and is provided with an elongated aperture 27 into which extends a pin 28 projecting outwardly from the plate 15 through a slot 29 in the ring 17 and a corresponding aperture in the plate 21. The inner end of the lever 25 is slotted at 30 and co-operates with a clamping screw 31. The point 26 being stationary an oscillatory movement of the lever 25 will cause the 95 lowermost ring 15 to be shifted back and forth. A similar lever 32 is pivoted at 33 on another of the pivot pins 20 and co-operates with the pin 34 on the intermediate ring 17 to oscillate the latter whereby all of the bell crank arms 22 may be simultaneously 100 adjusted toward or from their respective table slots 11. This lever is also secured in operative position by a clamping screw 35. The feeding table is mounted in a hori- 110

zontal position upon the upper end of a vertical shaft 36 operatively connected with a portion of a button turning machine (not shown), with which said feeding mechanism 5 coöperates.

Arranged at one side of the feeding table 10 is a platform 37 on which a quantity of the button blanks may be retained. The surface of this platform lies in the plane of 10 the upper face of the feeding table and its adjacent edge is curved and arranged in juxtaposition thereto, so that the button blanks may be readily transferred from the platform into proper position on the feeding 15 table and adjusted by the attendant beneath the springs 13 and in engagement with the gage fingers 16 and 22.

I claim as my invention:

1. In a blank feed table, the combination 20 with a table plate arranged to receive a plurality of blanks, of a ring rotatably adjustable thereon and provided with a plurality of spaced outwardly projecting fingers adapted to position said blanks at prede- 25 termined points upon the table.

2. In a blank feed table, the combination with an annular plate having its periphery provided with spaced notches, of a ring journaled on the plate and provided with 30 outwardly projecting fingers located between the notches, said fingers extending beyond the inner ends of the notches, and means for securing the ring with its fingers in adjusted position relatively to said 35 notches.

3. In a blank feed table for button making machines, the combination with an annular plate having its periphery provided with spaced notches, and a central project- 40 ing hub portion, of a ring surrounding the hub and provided with fingers correspond- ing to said notches, a pivoted lever arm and an operating connection between it and said ring to adjust the latter and simultaneously 45 move its several fingers relatively to their respective notches.

4. In a blank feed table, the combination with an annular plate and a ring thereon having outwardly extending spaced fingers, 50 of blank centering members above said ring and adjustable outwardly relatively to the fingers.

5. In a blank feed table for automatic ma- 55 chines for operating upon blank work pieces, the combination with an annular plate provided with a plurality of spaced notches in its periphery, a plate overlying it and having fingers arranged between said notches and forming side gage members and 60 means for adjusting them relatively to the notches, of centering gage members above the notches and adjustable inwardly and outwardly relatively thereto.

6. In a blank feed table for automatic ma- 65 chines for operating upon blank work pieces,

the combination with a table plate having an edge provided with notches and a gage plate adjustable thereon having fingers adapted to be located relatively to said notches to determine the lateral position of blanks in respect to said notches, and gage members adjustable inwardly and outwardly relatively to the edge of the table plate for varying the position of blanks placed on the table plate. 70

7. In a blank feed table for automatic machines for operating upon blank work pieces, the combination with a table plate having an edge provided with notches and a gage plate adjustable thereon having fingers adapted to be located relatively to said notches to determine the lateral position of blanks in respect to said notches, of a plurality of pivoted levers having their outer ends positioned relatively to said lateral gage fingers and an adjusting plate 80 engaging the inner ends of said levers for simultaneously adjusting them. 85

8. In a blank feed table for automatic machines for operating upon blank work pieces, the combination with a table plate, a gage plate mounted thereon having spaced fingers adapted to determine the lateral position of blanks placed on the table and means for adjustably securing the plate on the table 90 with its several arms fixed relatively to given centering points on said table, of a plurality of pivoted crank arms having their outer ends arranged to coöperate with the gage fingers to determine the innermost 95 position of blanks, an adjusting member co-operating with the inner ends of the cranks and adjusting devices for moving the member to simultaneously operate said cranks. 100

9. In a feed table, the combination with 105 a circular table plate, a circular gage plate of smaller diameter arranged centrally thereon and provided with a plurality of outwardly projecting gage fingers, devices for rotating the plate to adjust the fingers 110 relatively to given points for centering blanks on the table plate, of crank arms each having its outer end arranged to position the innermost edge of a blank, an adjusting plate revolvably supported on said 115 table and coöperating with the inner ends of the cranks and means for moving the adjusting plate relatively to the gage plate.

10. In a feed table, the combination with 120 a circular table plate provided with equidistantly spaced notches in its periphery, a gage ring having outwardly projecting fingers located between the notches and an adjusting lever coöperating with the ring to revolve the latter, of pivotally mounted bellcrank levers each having its outer end positioned in proximity to one of said notches, an adjusting ring also journaled on the table having notches embracing the inner ends of said cranks, and a pivoted lever 125 130

operatively connected with said adjusting ring for shifting it relatively to the gage ring.

11. In a feed table, the combination with a circular table plate provided with equidistantly spaced notches in its periphery and a central hub, a gage ring on the hub having fingers projecting between the notches and an adjusting lever operatively connected 10 with said ring, of a plurality of pivotally mounted gage fingers having their ends ar-

ranged in proximity to the slots in the table, an adjusting ring journaled on the hub and engaging said pivoted gage fingers for moving the latter inwardly or outwardly, an adjusting lever for operating said adjusting ring and work clamping springs projecting outwardly above the table plate. 15
